VENTILATING WINDOW FOR BARNs

Howard J. Ferris, Harvard, Ill., assignor to Starline Inc., Harvard, Ill., a corporation of Illinois

Application May 1, 1936, Serial No. 77,374

4 Claims. (Cl. 189—69)

An object of this invention is to provide a simple and efficient form of ventilating window for barns in which a single side member will serve for all sizes of sash regardless of their width or height.

Another object is to provide a frictionless means for carrying the sash in the frame.

Another object is to provide a positive lock for the window at all adjusted positions in the frame.

Still another means is to provide a means for readily breaking the sash loose when it becomes frozen in the frame.

These and other objects, as will hereinafter appear, are fully described in the following specification and shown in the accompanying drawings, in which—

Figure 1 is a perspective of a window frame and sash showing the latter in closed position;

Figs. 2 and 3 are enlarged partial sections on the lines 2 and 3 respectively of Fig. 1;

Fig. 4 is a slightly enlarged view partly in section on the line 4—4 of Fig. 1;

Fig. 5 is a partial enlarged section on the line 5 of Fig. 4;

Fig. 6 is a partial enlarged horizontal section on the line 6 of Fig. 4;

Fig. 7 is a partial side elevation of the lower portion of the frame partly broken away;

Fig. 8 is a partial enlarged horizontal section on the line 8 of Fig. 7;

Fig. 9 is a partial enlarged front elevation of the lower left-hand corner of the frame and sash showing the lifting bar; and

Fig. 10 is a partial enlarged section on the line 10 of Fig. 9 showing the lifting bar moved to a position 90° from that of Fig. 9.

The embodiment illustrated comprises a window frame 11 made up preferably of Z-bars 12 welded or otherwise secured together at the corners to form a rigid substantially integral frame. Within the frame and at the two sides are secured side members or wings 12 which are preferably triangular in form, the upper and

front edges being rolled at 12a as shown in Fig. 5, with a bent iron bar 13 rolled in as shown in Figs. 1 and 4, thereby further stiffening the side members and forming smooth corners. A tie rod 14 having threaded ends as shown in Fig. 2, 50 serves both to connect the side members and to serve as a rigid spacer therefor, nuts 15, one on each side of each side member 12, adjustably spacing these members. A roller 16 is journaled on the tie rod 14 and is provided with washers

55 17, one on each side of it, the inner washer be-

ing positioned by means of ears 14a struck from the rod 14.

Within and near the upper end of the side member is an arcuate member or strip 18 which is spot-welded to the inside of the side member, and preferably being of Z-shape formation, extends inwardly therefrom as shown in Fig. 5. This arcuate strip is preferably made concentric with the bottom inner edge of the window frame, and it is provided with a series of notches 19, 10 the purpose of which will later be explained, and terminates at its outer end in a beveled surface 20.

Within the window frame is a sash 21 made up of top, bottom and side members and cross bars 22, these parts being electrically welded together and carrying panes of glass 23, the whole being assembled in any well known manner. With the sash in closed position, as shown in Figs. 1 and 4, the sash, which preferably has a Z-bar 21a at the bottom, rests on the frame 11. The sash is shorter than the window, leaving a space 24 (Fig. 4) to permit the window to move, as will now be explained.

At each side of the sash is welded a clip 25 having an extension 26 which extends laterally from the sash and engages the notches 19 of the arcuate strip 18, as shown in Fig. 5. It also engages the forwardly and downwardly inclined surface 20, as shown in Fig. 4, thereby holding the sash firmly against the frame closing the window opening. Thus it will be seen that by lifting the sash as by means of handles 27 and pulling the upper portion of the window toward the rod 14, the extensions 26 are disengaged from the inclined portions 20 and may be made to engage with any one of the notches 19 of one of the arcuate strips and with the corresponding notch of the arcuate strip on the other side member. Thus the sash is able to rock about its lower edge, thereby permitting air to enter at the top.

The sash 21 is provided at each lower side edge with a pin 28 (Fig. 4) which extends laterally and lies behind an angle 29 (Fig. 6) which extends to about the height of the top of the arcuate strip 18 so as to prevent the sash from being accidentally readily removed from the window during the lifting operation. This angle is struck inwardly at 29a, as shown at the bottom of Fig. 7 to force the lower portion of the sash firmly up against the window frame.

In order to provide a means for lifting the sash from the bottom to various adjusted positions of the sash with respect to the frame, I have a series of ledges 30, 31, 32 which are

spaced from the angle 29 so as to provide passages 33 wide enough to permit the pin 28 to pass. These ledges are preferably downwardly and inwardly inclined to accommodate the pin as shown in the position 28' (Fig. 7) wherein the sash is raised, and the pins 28 rest on the ledges 30 while the upper portion of the sash rests on the rollers 16. These rollers serve to greatly reduce the friction, so that the sash can be raised from one position to another with great ease, four open positions of the sash being shown in Figs. 4 and 7. The uppermost position of the sash is that in which the sash is overbalanced by the greater weight of the outer end over the rollers 16, and the pins now in the position 28^a strike ledges 34 which serve to hold the sash in this position.

The wing or side members 12 are made so as to fit a small window and by this construction they can also be used to fit much larger windows. In other words, the window of Fig. 1 might, if desired, be substantially the height of these side members, or the window can be even higher than that shown and the side members can still be used. This is a feature of considerable importance as it enables windows of many sizes to be made up using a single size of side member. Likewise, the same side member can be used on both sides of the window, the only difference being that 30 the arcuate member has to be welded to the inside of the side member in both cases.

For breaking the windows loose when they become frozen, I have provided a lifting bar 35 (Figs. 1, 9 and 10) at each side. Each bar is 35 rotatably mounted on a pin 36 in the bottom of the main frame 11 and has a circular cam-like end 37 which is adapted to pass between the bottom of the frame 11 and the lower surface of the sash bottom 21^a as the lifting bar is rotated 40 about the pin 36 from the inoperative position of Figs. 1 and 9 to the lifting position of Fig. 10.

While I have shown and described but a single embodiment of my invention, it is to be understood that it is capable of many modifications. 45 Changes, therefore, in the construction and arrangement may be made which do not depart from the spirit and scope of the invention as disclosed in the appended claims.

I claim:

50 1. In a ventilating window, a frame, side members, one at each side of the frame and secured thereto, a tie rod connecting the upper outer corners of the side members, a sash adapted to be movable up and down in the frame and to bear 55 on the bottom of the frame, the top of the sash being movable out from the frame while the bottom of the sash remains nearly stationary, to assume various inclined positions, the sash being

adapted to pass over the tie rod and to assume positions at different elevations, and interengaging means on the frame and sash for holding the sash in various adjusted positions, the bottom of the sash being guided in a vertical portion of the frame for all said adjusted positions. 5

2. In a ventilating window, a frame, side members, one at each side of the frame and secured thereto, a tie rod connecting the upper outer corners of the side members, a sash adapted to be movable up and down in the frame and to bear 10 on the bottom of the frame, the top of the sash being movable out from the frame while the bottom of the sash remains nearly stationary, the sash being adapted to pass over the tie rod in 15 certain positions, a plurality of inwardly projecting ledges on the inside of the frame arranged in pairs at the same height in the frame, and an outwardly projecting protuberance on each lower corner of the sash for engaging selected pairs of 20 ledges to position the sash at various adjusted elevations.

3. In a ventilating window, a frame, side members, one at each side of the frame and secured thereto, a tie rod connecting the upper outer corners of the side members, a sash adapted to be movable up and down in the frame and to bear 25 on the bottom of the frame, the top of the sash being movable out from the frame while the bottom of the sash remains nearly stationary, the sash being adapted to pass over the tie rod in certain positions, a plurality of inwardly projecting ledges on the inside of the frame arranged in pairs at the same height in the frame, and an outwardly projecting protuberance on each lower 30 corner of the sash for engaging selected pairs of ledges to position the sash at various adjusted elevations, the ledges being downwardly and inwardly inclined. 35

4. In a ventilating window, a frame, side members, one at each side of the frame and secured thereto, a tie rod connecting the upper outer corners of the side members, a sash adapted to be movable up and down in the frame and to bear 40 on the bottom of the frame, the top of the sash being movable out from the frame while the bottom of the sash remains nearly stationary, the sash being adapted to pass over the tie rod in certain positions, a plurality of inwardly projecting ledges on the inside of the frame arranged in pairs at 45 the same height in the frame, an outwardly projecting protuberance on each lower corner of the sash for engaging selected pairs of ledges to position the sash at various adjusted elevations, and rollers on the tie rod over which the sash rolls 50 in the upper adjusted positions. 55

HOWARD J. FERRIS.
